(57) **CLAIM**

The ornamental design for an egg carton with bubble cell pockets, as shown and described.

DESCRIPTION

FIG. 1 is a bottom perspective view of an egg carton with bubble cell pockets, according to our new design;

FIG. 2 is a front elevational view thereof;

FIG. 3 is a rear elevational view thereof;

FIG. 4 is a right side elevational view thereof, the left side elevational view being a mirror image thereof;

FIG. 5 is a bottom plan view thereof;

FIG. 6 is a top front perspective view thereof;

FIG. 7 is a top rear perspective view thereof; and,

FIG. 8 is a top plan view thereof.

The broken lines illustrate portions of the egg carton with bubble cell pockets and form no part of the claimed design.

1 Claim, 6 Drawing Sheets
